UNITED STATES PATENT OFFICE

JAMES H. RAND, JR., OF TONAWANDA, NEW YORK, ASSIGNOR, BY MESNE ASSIGNMENTS, TO REMINGTON RAND INC., OF NEW YORK, N. Y., A CORPORATION OF DELAWARE

INDEX DEVICE

Application filed June 11, 1925. Serial No. 36,365.

This invention relates to improvements in index or record devices, more particularly to index cabinets in which a plurality of slides, panels or supports are arranged so as to move from an inoperative position in a cabinet to an operative position extending out of said cabinet. The panels or slides are of the type adapted to support a plurality of records, cards or card holders arranged thereon in overlapping relation with their edges exposed one beyond the other for the purpose of exposing data relative to subject matter on the cards.

The invention further relates to a table or support for a bank or series of such cabinets.

In a relatively large installation of cabinets of this character, it is desirable that the cabinets be arranged so that all the records in the cabinets are readily accessible with the least effort on the part of the user and that the cabinets be constructed and arranged so as to contain the maximum number of records in a minimum of space.

Some cabinets heretofore provided have been in the form of boxes or cases open at the front and constructed to support a plurality of horizontal slides or panels carrying the record matter or cards, and the slides have been constructed so as to permit them to be pulled out and extended downwardly to permit the records to be viewed or worked upon. This arrangement has necessitated the provision of a relatively wide shelf or support in front of the cabinets to support the front ends of the trays in operative position, and the various movements necessary to bring the records to position for use required considerable effort.

The objects of the present invention are to provide a table or similar support of novel construction, and to arrange a plurality of cabinets cooperating with said support in such manner that each cabinet will be disposed at substantially the same distance from the user, whereby the user may have ready access to all the records in the series of cabinets without moving from one position to another; also to provide a plurality of such cabinets with means whereby each cabinet may contain a plurality of vertically dis-

posed record bearing slides or members, any one of which may be readily moved or projected out of its cabinet to an operative position, whereby all the records are equally visible at a comfortable level relative to the eyes of the user; also to provide a table or support for a series of cabinets of the character described having a plurality of recesses or apertures in its supporting surface for the reception of the cabinets; also to construct and arrange the cabinets so that each cabinet is adapted to support a plurality of the slides or panels in an ascending series whereby by providing each panel with an index member or tab, the contents of all of the slides or panels in the entire series are visible from one position.

Other objects are to provide the cabinets with a plurality of independent, readily removable guide members or devices for the panels adapted to be disposed flatwise, one behind another, so as to extend vertically in the cabinet with their upper edges exposed one behind another; also to provide each guide member with means for releasably supporting a record bearing slide within the cabinet when not in use, and to provide manually actuated, mechanical means for moving the slide relatively to said guide member to a position in which the records thereon are visible and accessible.

Other objects are to improve record cabinets or devices of the character stated in the other respects hereinafter specified and claimed.

In the drawings:—

Fig. 1 is a front elevation of a table or support and a plurality of index or record cabinets embodying the invention.

Fig. 2 is a plan view thereof with one cabinet omitted.

Fig. 3 is a transverse, vertical section thereof on line 3—3 Fig. 2.

Fig. 4 is a front elevation on an enlarged scale, of one of the guide devices or containers for the record bearing panels or slides showing a panel therein in its inoperative position.

Fig. 5 is a top plan view thereof.

Fig. 6 is a vertical, sectional elevation thereof on line 6—6, Fig. 4.

Fig. 7 is a transverse, sectional elevation, partly broken away, of the parts shown in Fig. 4, but with the record supporting panel 5 partly projected out of the guide device.

Fig. 8 is a fragmentary view similar to Fig. 7, showing a slightly modified construction, and with the record panel in its inoperative position.

Fig. 9 is a perspective view showing the upper portion of three of the guide devices for the record supporting panels, with one of said panels projecting outwardly from its 10 guide, in position to permit the record devices thereon to be worked upon.

Fig. 10 is a fragmentary, horizontal section, on an enlarged scale, on line 10—10, Fig. 7.

Fig. 11 is a fragmentary, transverse section of a portion of one of the panels, showing a plurality of the record devices thereon.

Fig. 12 is a fragmentary, vertical, transverse section on an enlarged scale on line 12—12, Fig. 4.

Fig. 13 is a fragmentary, horizontal section, on an enlarged scale, on line 13—13, Fig. 7.

Fig. 14 is a similar view on line 14—14, Fig. 8, of the modified construction.

Fig. 15 is a fragmentary, perspective view of the member for supporting the holding dog of one of the slide containers.

Fig. 16 is a transverse, sectional elevation of a desk and cabinet of slightly modified construction.

In the embodiment of the invention disclosed in Figs. 1-3, a table or support A is shown having associated therewith a plurality of index or record cabinets B each arranged to contain a plurality of vertical slides 20 adapted to be moved to display a plurality of records or cards C preferably supported thereon in overlapping, nested relation, the slides being readily accessible, and all substantially equally visible by a user seated approximately at the position X, Fig. 2.

For this purpose, the cabinets B are arranged so as to extend radially relatively to said position, and are disposed in a compact, arcuate series so that the front of each cabinet is substantially the same distance from a user seated at X. Each end cabinet of the series is therefore disposed near the front edge of the table top 22, and the intermediate cabinets are disposed rearwardly of said end cabinets so as to provide a substantial working space 23 in front of the cabinets on said top 22. The table top 22 is disposed approximately at the usual height for comfortable use by a person sitting at the position X, and to enable the records to be viewed and worked upon from said sitting position, 60 the cabinets B are arranged in recesses or

pockets 24 in the top 22 with their front edges 25 substantially flush with said top, and the slides 20 are disposed vertically on edge one behind the other in parallel arrangement with their top edges projecting 70 one above another from front to rear of the cabinets.

Each of the slides may be provided with a suitable index tab or indicator 26 at its upper edge adapted to bear suitable data indicative 75 of the contents of the slide, see Figs. 4 and 7.

To enable the slides 20 to be vertically supported, the cabinets B are constructed in the form of open topped boxes or cases each having vertical front and rear walls 28 and 29, and vertical side walls 30, and each slide 20 is disposed within a vertical guide member or container 31.

The slides 20 may be of any suitable construction adapting them to support the cards or record members C in overlapping arrangement, and in the construction shown, each slide is formed of sheet metal and comprises a back wall or member 33, inturned flanged sides 34 beneath which the lateral lugs 35 of the cards extend so as to be detachably and slidably retained on the slides, and a bottom flange or stop 36 upon which the lower edge of the bottom card rests. The cards are preferably nested in a well known manner and are disposed with their free, or record displaying edges or pockets 37 at the top, see Fig. 9, so that the cards or record members may be swung downwardly as shown in that figure for the purpose of exposing the 100 surfaces of the cards. The cards C of themselves constitute no part of the invention, and any other suitable form of card, card holder or record member adapted for use on a slide of the character described may be 105 used, and for the sake of brevity, these members will be hereinafter referred to as cards.

Each guide member or container 31 is also preferably formed of sheet metal and comprises a vertical back wall 40, opposite forwardly extending side portions 42 and 43 having straight side edges 42a, 43a and flat front faces 42b and 43b respectively. The faces 42b and 43b are extended inwardly to form parallel overhanging vertical flanges 44, and the flanges 34 of the slides are adapted to engage beneath these flanges 44 and be guided and retained in the container by said cooperating flanges between said side portions 42 and 43 of the container, see Figs. 4 and 5. 115

The containers 31 are thus adapted to be detachably supported and arranged flatwise one behind another in the cabinets with their rear walls 40 abutting against the front faces 42b, 43b of adjacent containers, and the containers are maintained in a compact series by the engagement of their side faces 42a and 43a engaging the side walls 30 of the cabinets. 125

To permit the upper edges (and indicators 130

26 when used) of the slides to be arranged in a rearwardly ascending series in each cabinet, the containers 31 are supported in the cabinets with their bottom walls or edges 47 5 engaging an upwardly and rearwardly extending fixed member or part 48 which, in the construction illustrated in Figs. 1-3, also constitutes the bottom of the cabinet. The top edges of the sides 30 of the cabinets are 10 preferably parallel with the bottom 48, so that the containers and slides are enclosed or confined with only their upper portions normally exposed at the top of the cabinet.

When the individual cards bear index matter as in Fig. 9, each top card in each slide 15 constitutes a visible index for that slide, and should the cards be rearranged at any time, the card which is moved to the top of the slide will be an index for the slide, so that 20 collectively the headings thus provided will be the means for locating the matter on the other cards. Thus the index tabs 23 are only required for particular uses.

Any suitable means may be provided for 25 the purpose of holding the slides 20 in their lower positions. As shown in Figs. 4-7 and 9-13, the bottom portion of each slide is formed or provided with a pair of depending arms 50 and 51. One of these arms, as for 30 instance arm 51, is constructed to be engaged by a suitable detent. The arm 51 is apertured at 52 for the reception of an offset shoulder 53 on a dog 54 pivotally mounted at 55 in the bottom of the side portion 43 of the container 35 31, said portion being hollow as shown Figs. 7-13. The dog 54 is provided with an ear or lug 56 which is normally engaged on its outer side by a spring member 57 to hold the shoulder 53 of the dog in the aperture 52 of the 40 slide, thus positively holding the slide in its retracted, lower position.

The manually operable means for retracting and releasing the dog 54 from the slide 45 may also be of any suitable construction, that shown comprising a cam or wedge block 59 having an inclined face 60 adapted to engage the inner side of the lug 56 of the dog. The block 59 is rigidly attached to the lower end of an operating rod or member 62 extending 50 vertically in a housing 63 which constitutes a part of the side portion 43. The upper end of said rod 62 projects out of a hole in the top 63a of the housing and is provided with a 55 knob 64 at its upper end. A coil spring or other resilient member 65 is adapted to bear against a fixed stop 66 within the housing 63 and against a fixed collar 67 on the rod, said spring being adapted to press the collar 60 against the top piece 63a and hold the rod and the block 59 in their upper positions. By depressing the rod 62, the cam face 60 of the block 59 will engage the lug 56 and move it to the right as shown in Fig. 7 thus freeing 65 the slide 20 from the holding action of the

dog 54. Other means for releasing the slide may be used.

The guide member or container 31 is provided with means connected to the slide 20, for automatically projecting it upwardly to 70 its exposed position as soon as the dog is released from the aperture 52. Any suitable means may be employed for this purpose, that shown, see Fig. 7, comprising a spring actuated, rotatable roller 70 horizontally arranged in a housing 71 at the bottom of the container and journaled in end bearings 72 thereof. This rod 70 has attached thereto one end of a cord or cable 73 which passes 75 upwardly in another housing 74 in the side portion 42 of the container and over a pulley or roller 75 at the upper end thereof, and thence downwardly outside of said housing to the lower end of the slide 20, where the end of the cord is detachably secured to a clip 80 or fitting 76 rigidly secured on the depending arm 50. A coil spring 78, surrounding the rod 70 and having one end secured to said rod and its other end to a part of the housing 71, is adapted to rotate the rod so as to wind 85 the cord 73 thereon and exert an upward pull on the slide 20. The tendency of the spring is to hold the slide in its upper position, and when the slide is lowered, the spring is placed under tension, the slide being held by the dog 90 54. Therefore, by merely depressing the rod 62, the slide is released and the spring 78 will at once rotate rod 70, wind up the cord 73 and elevate the slide. When the user has finished 95 with the slide, it is only necessary to depress the same into the container until the aperture 52 is opposite to the dog 54 whereupon the spring 57 will move the dog into its locking position therein. Other suitable slide projecting mechanism may be used if desired. 100

Stop means are preferably provided whereby the outward movement of the slide 20 is limited relatively to the guide member or container 31 so as to not only prevent the slide from becoming disengaged from the 110 guide, but also to stop it in such position that it will be adequately supported in its projected position so as to be firm enough to enable the records to be worked upon. For this purpose the slide 20 is provided, near its lower end, with a lug or projection 79, which, when the slide moves upwardly is adapted to engage a stop member 80 formed on or secured to the top of the container. The lug 79 is so disposed that when it is in engagement with the stop 80, the arms 50 and 51 and lower part of the slide remain in the container and support the slide in its projected position. 115

In order that the container 31 may be produced in an efficient and practical manner, the housings 63, 71, and 74 are preferably in the form of separate units so constructed that the slide holding, projecting and controlling mechanisms can be assembled therein before the housings are attached to the container. 120 125 130

In the particular construction shown, the housing 63 is in the form of a sheet metal channel piece, see Fig. 13, the web 81 of which is slit lengthwise at the lower end and the two portions 82 thus produced are bent so as to extend in the plane of the flanges 83 of the channel piece and are apertured for the pivot 55 of the dog 54, see Fig. 15. The stop 66 may be formed or attached in the channel, 10 the rod 62 and spring 65 positioned in the housing and by then placing the housing in the container with the web 81 facing inwardly as shown, and the end of the rod 62 extending through the top 63a, the housing may 15 be secured in place with the mechanism in operative position, by welding or otherwise securing the flanges 83 to the container, after which the knob 64 is attached. The housing 71 is likewise of channel formation, and the rod 70 and spring 78 are readily assembled therein by bending up the integral pieces 72 to provide bearings for the rod. In this instance, the channel is secured by one of its flanges to the bottom 47 of the container. The 20 housing 73 is fashioned and secured in the container in a somewhat similar manner to the housing 61, the upper portion of the channel web being slit to provide bearing pieces for the pulley 75.

30 In the construction described, the slides 20 when released, are projected to their extreme outer position relatively to the containers, being restrained only when the lugs 76 engage the stops 80. If desired, however, means 35 may be provided whereby the slides may be held in a plurality of intermediate positions, which positions may be such as to expose only a few of the upper records. The modified form shown in Figs. 8 and 14 is adapted for 40 such purpose, the slide 20a in this instance being formed with a plurality of spaced apertures 85 along one of its vertical sides adapted for selective engagement of a spring 45 pressed dog 86 with the slide. This dog is preferably pivotally arranged on the container 31a adjacent the upper end thereof and is adapted to be manually actuated by a cam block 87 fixed on an operating rod 88. In 50 this case, a stop lug 89 is formed on the extreme lower end of the slide and is adapted to engage either the shoulder of the dog 86, or a fixed stop 90 near the top of the container 31a. The stop 90 is so disposed that the slide will extend into the container a 55 sufficient distance for proper support when in projected operative position.

It should be understood that in this modified construction a spring and cable mechanism is provided substantially as in the first 60 construction, so that by depressing the rod 88 and block 87 to release the slide 20a, and then relieving the pressure on said rod, the dog will enter that one of the apertures 85 which happens to be at, or about to arrive at 65 the shouldered part of the dog.

In the modified construction, Fig. 16, there is shown a desk A' having a flat top 22a and one or more apertures 24a each of which receives a cabinet B'. The cabinets, as in the first construction, are adapted to receive a plurality of the containers 31 in each of which a slide 20 is disposed, and which supports a plurality of record members in overlapping relation, as before. The slide 20 is adapted to be releasably held in and projected from the container by the means heretofore described, and which are actuated by the push rods 62.

The cabinets, in this construction, however, are not provided with means for supporting the container and slides in ascending series, but are each formed with a horizontal bottom plate 100 adapted to support the slides so that their top edges are disposed in horizontal relation from front to back of the cabinet. This arrangement is desirable under certain conditions, and when not in use, each cabinet may, if desired, be concealed by a cover (not shown) placed over the openings 24a so as to form a substantially smooth desk 90 top.

The index or record devices described are very practical and of large capacity relatively to the space occupied, and the slides and the cards or record members being vertically disposed on the vertical slides, are all substantially equally accessible and equally visible from the position X at which the user is sitting. Moreover, the indexes in the various cabinets are rendered available for use by only a slight effort on the part of the operative, it only being necessary to depress the operating rod of the required slide, whereupon it will be quickly projected to its operative position in which the upper, exposed edges of the cards are clearly visible to the operative, without changing his position.

After use, a slight downward pressure on the slide returns the same within its cabinet where it is positively retained until again projected. Furthermore, the index may be rearranged from time to time to adapt it to particular circumstances or conditions by lifting the containers with their slides out of the cases and transferring them to other 115 cases or transposing them in the cabinets.

I claim as my invention:

1. In a record device, a plurality of slides each adapted to bear a plurality of record members thereon in overlapping, offset arrangement, a plurality of guide containers each of which is adapted to receive one of said slides, an open-topped case in which said containers are adapted to be disposed one behind another with the upper portions of said slides exposed, each of said containers having manually actuated means for projecting the slide outwardly to an operative position so that said record members may be 125

flat on the tops of the remaining slides for convenient reference.

2. In a record device, a plurality of slides each adapted to hingedly support a plurality of record members thereon in overlapping, offset arrangement, an open-topped case in which said slides are adapted to be disposed one behind another with the upper portions of said slides exposed, and means in said case adapted to be manually actuated to move said slides outwardly of said case to a position so that said record members may lie flat in operative position on the top of the remaining slides.

3. In a record device, a slide adapted to hingedly support a plurality of record members in overlapping, offset relation with their edges exposed one beyond another, a container for said slide comprising a back, and side portions embracing said slide and adapted to permit vertical movements thereof in said container and guide the same in said movements, said slide retaining the record members in an inoperative position when housed within said container, means on said container for releasably holding said slide in said housed position, and said container having manually operable means adapted, when actuated, to project said slide to an operative position extending out of said container with certain record members extending into operative position substantially at right angles to said slide.

4. In a record device, a plurality of slides adapted to hingedly support record matter in overlapping offset position, a container for each slide constructed to permit vertical movements of said slide therein, a spring-pressed latch in each container adapted to engage a part on said slide to releasably hold said slide in a housed position within said container, a manually operable member adapted to engage and retract said latch from engagement with said part to release said slide, and spring-actuated means in each container for projecting said slide out of said container when said latch is retracted so that said record matter is moved from nested to operative position, at substantially right angles to said slides.

5. In a record device, a slide adapted to support record matter in overlapping offset position, a container for said slide constructed to permit vertical movements of said slide therein, a spring-pressed latch on said container adapted to releasably engage a part on said slide to hold said slide in a housed position within said container, a manually operable member adapted to engage and retract said latch from engagement with said part to release said slide, a roller in said container, a spring secured to said roller and which is under tension when said slide is in said container, and which, when said latch is retracted, is

adapted to rotate said roller, a cable or the like attached to said roller and to said slide which is adapted to be wound on said roller when the same is rotated by said spring to project said slide out of said container.

6. In a record device, a slide adapted to support record matter in overlapping offset position, a container for said slide constructed to permit vertical movements of said slide therein, a spring-pressed latch on said container adapted to engage a part on said slide to releasably hold said slide in a housed position within said container, a manually operable member adapted to engage and retract said latch from engagement with said part to release said slide, spring-actuated means on said container connected to and for projecting said slide out of said container when said latch is retracted, a housing secured in said container in which said spring-pressed latch and said manually operable member are mounted, a housing secured in said container in which said spring-actuated slide projecting means are mounted.

7. In a record device, a slide adapted to support record matter in overlapping offset position, a container for said slide constructed to permit vertical movements of said slide therein, a spring-pressed latch on said container adapted to engage a part on said slide to releasably hold said slide in a housed position within said container, a manually operable member adapted to engage and retract said latch from engagement with said part to release said slide, spring-actuated means on said container for projecting said slide out of said container when said latch is retracted, and a housing secured in said container in which said spring-pressed latch and said manually operable member are mounted, and integral portions on said housing adapted to form bearing portions for said latch.

8. In a record device, the combination of a plurality of cabinets, a support having a plurality of apertures for the reception of said cabinets, a plurality of record-bearing slides for each cabinet, and a separate container for each slide arranged in said cabinets, means for vertically supporting a number of said containers in each cabinet with their upper portions arranged one behind and above another whereby the upper portions of the slides are all substantially visible from a given position, means on each container for releasably holding its slide within said container, means adapted to be manually actuated to release said holding means, and means adapted to automatically project said slide out of said container when said holding means have been released.

9. An index file, comprising a cabinet, a plurality of containers independently and removably positioned in said cabinet in adjacent relation, a record carrying slide member slidably mounted in each container, and

manually controlled means in each container for projecting the slide outwardly therefrom.

10. An index file, comprising a cabinet, a plurality of containers independently and removably positioned in said cabinet in adjacent relation, a record carrying slide member slidably mounted in each container, and self-contained operating means in each container for projecting the slide outwardly therefrom.
